UNITED STATES PATENT OFFICE.

WALTER J. SCHWEN, OF BLUE EARTH, MINNESOTA.

APPARATUS FOR DISPLAYING MERCHANDISE.

Application filed February 11, 1924. Serial No. 692,095.

To all whom it may concern:

Be it known that I, WALTER J. SCHWEN, a citizen of the United States, residing at Blue Earth, in the county of Faribault and 5 State of Minnesota, have invented certain new and useful Improvements in Apparatus for Displaying Merchandise, of which the following is a specification.

This invention relates to apparatus for 10 displaying merchandise, and more particularly to means for normally supporting a box or container in a show case for displaying the contents, and permitting movement of the box to a second position for dispensing 15 purposes.

An object of the invention is the provision of means for normally supporting a container in a substantially vertical position adjacent the front of the show case and permitting the container to be lowered to a horizontal position when merchandise is to be dispensed.

A further object of the invention is the provision of apparatus of this character 25 which may be adjusted both laterally and longitudinally of the show case for the purpose of supporting containers of various sizes.

In the accompanying drawings, I have 30 shown one embodiment of the invention. In this showing:

Figure 1 is a perspective view of a show case showing the invention applied,

Figure 2 is a transverse vertical sectional 35 view,

Figure 3 is a horizontal sectional view with the containers removed,

Figure 4 is a detail perspective view of one 40 of the supporting members disassembled, and,

Figure 5 is a similar view of a spring.

Referring to the drawings, the reference 45 numeral 1 designates the bottom of a show case of ordinary construction. The show case is provided with end walls 2, formed of glass or other transparent material and a top 3. The front 4 of the show case is arranged at an angle to the vertical, as shown. The bottom of the show case is provided 50 with a pair of spaced slots 5, and a base member 6 is received in these slots. As shown, the base member is provided with angular end portions 7 which enter the slots, as shown in Figure 3 of the drawings, and 55 permit adjustment of the base longitudinally of the show case. A plate 8 is mounted

on the base. This plate is provided with an elongated slot 9, adapted to receive a pin or bolt 10, carried by the base to permit adjustment of the plate laterally of the show 60 case. The forward end of the plate is provided with a pair of ears 10. A supporting member 11 is hingedly connected to the plate 8. As shown, the forward end of the supporting member is provided with ears 65 12 and the ears 10 and 12 are provided with alined openings for the reception of a pivot pin 13. The front of the supporting member is provided with a flange 14, adapted to form a support for a box or container 15 70 when the supporting member is in raised position. A spring, formed of a single piece of wire, is adapted to normally retain the supporting member in raised position. As shown, the spring is provided with a coil 75 16, adjacent each end and these coils are arranged on the hinged pin 13. The ends 17 of the wire engage the plate 8 and the intermediate portion forms a loop 18 engaging the bottom of the supporting member. As shown, the upper end of the supporting member is provided with a hook or handle 19 to permit the supporting member to be lowered to the dotted line position shown in Figure 2 of the drawings, for the purpose 80 of dispensing merchandise.

The operation of the device will be apparent from the foregoing description. The containers are normally supported in an inclined position parallel to the front of the 90 show case, as shown in Figures 1 and 2 of the drawings, for the purpose of more efficiently displaying the merchandise contained therein. The loop 18 of the spring engages the back of the supporting member 11 to retain it in this raised position. When a customer indicates the merchandise he desires, the operator lowers the supporting member 11 to the dotted line position against the tension of the spring by grasping the hook 95 19 and the merchandise may then be readily removed from the container. The slot 9 permits lateral adjustment of the plate 8 and the supporting member to receive containers of different sizes and the base member 6 may be adjusted longitudinally in the 100 slots 5.

It is to be understood that the form of my 110 invention herewith shown and described is to be taken as a preferred example of the same, and that various changes in the shape, size, and arrangement of parts may be re-

sorted to without departing from the spirit of the invention or the scope of the subjoined claims.

I claim:

5. 1. The combination with a show case having spaced longitudinally extending slots in the bottom thereof, of a merchandise displaying device comprising a base having extensions adapted to enter said slots, a supporting member mounted on said base, said supporting member being adjustable on said base in a direction at right angles to said slots, means for supporting a merchandise container on said supporting member, and
10 means for normally retaining said supporting member in a raised position.
2. The combination with a show case having spaced longitudinally extending slots in the bottom thereof, of a merchandise displaying device comprising a base having extensions adapted to enter said slots, a supporting member mounted on said base, said supporting member being adjustable on said base in a direction at right angles to said
20 slots, means for supporting a merchandise container on said supporting member, and a spring engaging said supporting member to normally retain it in a raised position substantially parallel to the front of the show case.
25
3. In a device of the character described, a base, a plate adjustably mounted thereon, a supporting member hinged to said plate, means for retaining said supporting member
30

in a raised position, and means for supporting a merchandise container on said supporting member when it is in a raised position.

4. In a device of the character described, a base, a plate adjustably mounted on said base, a supporting member hinged to said plate, said supporting member being provided with a flange at its forward end adapted to support a merchandise container when the supporting member is in raised position, and a spring engaging said plate and said supporting member to normally retain said supporting member in raised position.

5. The combination with a show case having spaced longitudinally extending slots in the bottom thereof, of a merchandise displaying device comprising a base having angular extensions adapted to enter said slots, a supporting member mounted on said base, said supporting member being adjustable on said base in a direction at right angles to said slots, and being provided with a flange to support a merchandise container when the supporting member is in raised position, and a spring engaging said supporting member to normally retain it in a raised position substantially parallel to the front of the show case.

In testimony whereof, I affix my signature in presence of a witness.

WALTER J. SCHWEN.

Witness:

M. O. MADISON.
